UNITED STATES PATENT OFFICE.

JAMES BUSFIELD, OF HAVERHILL, MASSACHUSETTS.

LEATHER-SPLITTING MACHINE.

SPECIFICATION forming part of Letters Patent No. 629,062, dated July 18, 1899.

Application filed December 5, 1898. Serial No. 698,264. (No model.)

To all whom it may concern:

Be it known that I, JAMES BUSFIELD, a citizen of the United States, and a resident of Haverhill, in the county of Essex and State 5 of Massachusetts, have invented certain new and useful Improvements in Leather-Splitting Machines, of which the following is a specification.

This invention relates to that class of 10 leather-splitting machines which split small and perhaps otherwise useless pieces of leather through the middle, leaving a small portion unsevered, so that the piece may be laid open and its surface area nearly doubled. 15 In this class of machines it is very essential that the leather be split through the middle precisely in order that the split portions will be of equal thickness.

The object of my invention is to provide a 20 machine which will split the leather exactly through the middle and which does not require readjustment whether used on thick or thin leather.

A further object of my invention is to provide 25 an effective means for spreading the piece which is split and laying the same flat without injuring the "connecting-hinge."

For the better understanding of the main 30 features of improvement secured by my invention I will first refer, briefly, to the prior art.

The machines originally used for this purpose were provided with springs which bore 35 on the outer sides of the bearings, forcing the rolls together. These machines did unsatisfactory work, as it was impossible to adjust the springs so that they would always have the same tension. Therefore the rolls would not separate uniformly. These machines 40 were slightly improved by the Adams machines and some others by providing equalizing-levers of various forms between the rolls to overcome the uneven separation. They were found to be but a slight improvement.

45 over prior machines, for the reason that as the equalizing-levers transmit no force there is bound to be a certain amount of lost motion at the joints as the bearings move back and forth. As the movement of the rolls is slight 50 in any case, a slight amount of lost motion between the rolls will neutralize nearly all the effect of the equalizing parts. In the Smith

machine a single spring is arranged so as to force a pair of bearings together instead of two springs, as in the Adams machine. In 55 this machine the spring acts to draw down a block which is arranged to slide in a slot at right angles to the line of motion of the rolls. Two links are pivoted to the block at one end and extend diagonally and are pivoted at their 60 opposite ends each to a bearing-box. The action of the spring in drawing the block downward draws the rolls together. The main difficulty with this machine is that the spring acts to draw the bearings down on their ways 65 as much as it acts to draw them together, causing the bearings to work hard and possibly stick. For this reason the spring must be placed under considerable tension, so that the rolls will be sure to grasp the leather with 70 sufficient pressure to force a thin piece of leather through the rolls, and a thick piece would be gripped with considerable force. Moreover, as the leather passes between the rolls it must not only overcome the tension of 75 the spring, but must also overcome the friction of the bearing-boxes on their ways. All of this causes the fluted rolls to sink into the leather to a considerable extent. If the leather which passes through the machine is soft and 80 pulpy, the flesh side thereof will be much softer than the grain side. The result is that the excessive pressure on the leather will compress one side more than the other, with the obvious result that the leather will not be 85 split in the middle, no matter how evenly the rolls may separate, it being split so that the flesh side will be thicker than the grain side.

According to my invention I have combined 90 the advantages of the machines above referred to in a single machine in a manner that also obviates the disadvantages of these machines. I accomplish this result by pivoting a pair of levers at each end of the machine so that they each bear against the outside of their respective bearing-boxes and force them together. I then provide a pivotal connection between 95 each pair of levers and arrange a single spring so that it will operate upon this pivotal connection in such a manner that the levers will 100 force the rolls together. I avoid the friction caused in the Smith machine by drawing the bearings down on the ways by having the force which moves the bearings together act

in their line of motion, and yet I secure the advantage of having a single force act on the equalizing parts so that they will always be drawn in one direction, and if the parts become worn there will still be no chance for lost motion. By this arrangement friction of the parts is reduced to a minimum and the springs may be set so that the rolls may grip the leather as lightly as desired.

I have also improved existing machines in certain other minor details, as will hereinafter appear.

In the drawings, Figure 1 is an end elevation of the machine. Fig. 2 is a cross-section through the center thereof on the line $\alpha\alpha$ of Fig. 1. Fig. 3 is a plan view. Fig. 4 is a cross-section on the line yy of Fig. 3. Figs. 5 and 6 are side elevations of the right and left sides of the machine, respectively. Figs. 7, 8, and 9 are detail views of the splitting-knife support, Fig. 7 being a cross-section on line zz of Fig. 8, Fig. 8 a cross-section on line nn of Fig. 7, and Fig. 9 a cross-section on line oo of Figs. 7 and 8. Figs. 10, 11, and 12 are detail views of the support for the straightening-knife, Fig. 10 being a rear, Fig. 11 a side, view thereof, and Fig. 12 a cross-section on the line pp of Figs. 10 and 11. Figs. 13 to 17, inclusive, are detail views of the splitting-knife, Figs. 13, 14, and 15 being side, front, and rear end views thereof, respectively, and Figs. 16 and 17 being cross-sectional views on the lines qq and rr , respectively, of Fig. 13. Fig. 18 is a detail cross-section of one of the stop-sleeves, the several stop-sleeves shown in the drawings being identical in construction. Fig. 19 is a detail face view of one of the toggle-levers.

The same reference numerals and letters indicate similar parts throughout all the views.

The ordinary fluted feed-rolls 1 are journaled at each end in the sliding bearings 2. These bearings slide in horizontal slots 2', formed in the frames a and b of the machine, the sides of said slots forming guideways 2'', between which the bearing-boxes fit nicely and slide readily, so that free horizontal movement is permitted, but vertical movement is prevented. The splitting-knife 3 is supported precisely midway between the fluted portions of the rolls 1, slightly below the axis thereof. A knife 4 for straightening the edge of the leather is supported in the bracket 5, which latter is supported on frame a by arms 5' and is arranged to be adjusted vertically therein in any well-known manner. I prefer, however, to provide the vertical end of the bracket 5 with a dovetail groove 6, in which the knife 4 fits. The bracket 5 is partially split, as shown in Figs. 1, 10, and 12 at 5, so that the grooved portions thereof may be clamped together by the screw 7 to hold the knife firmly in place. This bracket 5 is provided with a spout or channel 8, which is so arranged that it will catch the strip of leather which is taken off by the knife 4 as it straightens the edge, thus preventing this

waste strip from dropping into the receptacle which receives the split leather. An angular-shaped guide 9, which has the vertical face thereof grooved, is adjustably secured to the top of frame a of the machine, so that the center of the groove is in the same vertical plane as the edge of the splitting-knife and somewhat in front of the vertical line 75 from the edge of the straightening-knife 4.

If the edge of the leather piece which is to be left unsevered is straight, the bottom of the groove in guide 9 may be set directly in line with the knife 4, so that no straightening-chip will be taken off, and the waste of leather will therefore be prevented. The particular position at which the guide 9 may be set in order to secure the greatest saving of leather varies considerably according to the shape of the leather pieces, and a ready means of longitudinal adjustment thereof is therefore desirable. To secure this adjustment, the top of the frame a is provided with two ribs a' , between which guide 9 is fitted 90 to slide longitudinally. A screw 9' clamps the guide in position, a slot 9" in said guide, through which the screw passes, permitting longitudinal movement thereof when the screw is loosened.

Levers 10 are pivoted in pairs on pivots 11 at each end of the frame. These levers are provided with inward projections 10' at their upper ends, (see Fig. 19,) having curved faces which engage the outer sides of the bearings 10. Blocks 12 are dovetailed into the vertical slots 13 of the frames a and b and are adapted to slide therein. Links 14 connect said blocks with the lower ends of said levers 10. Rods 15 are secured by any suitable means, 105 as by screw-threads, to said blocks 12 and extend down through the frame. The lower ends of said rods are screw-threaded to receive the nuts 16. Springs 17 are located between said nuts and the frame, and when the nuts are 110 screwed up sufficiently the springs will draw down the blocks 12, forcing the lower ends of levers 10 outwardly and pressing the bearings, and with them the rolls, toward each other. Springs 18 are located between each 115 pair of bearings and prevent the fluted portions of the rolls from coming in contact. Other means might also be used for this purpose; but the springs are preferably used, as they take up the jar as the rolls are forced together after the leather has passed between them. It will be seen that the springs 17 and 18 act in opposition to each other, the springs 17 being adjusted so that they are in equilibrium with springs 18 when the fluted portions of the rolls are just out of contact. A cross-bar 19 connects the rods 15 and slides thereon. A spreader or opening wheel 20 is carried by the shaft 21, said wheel being located directly below the end of the splitting-knife 3. This wheel is provided with a central groove 20', and at each side thereof are fluted or roughened portions 22. The width of the bottom of the splitting-knife should be 120 125 130

about equal to the width of the burred portions of the wheel 20. The sides of this wheel are tapered from the edge of the roughened portions to the shaft, as shown at 20", Fig. 4. 5 A second spreader-wheel 23 is journaled in brackets, so as to rotate freely on its shaft 24 directly in front of wheel 20 in close proximity thereto. Said wheel 23 is cylindrical in form and is provided with a central annular groove 25, the width of which is greater than the thickness of the leather which is ordinarily passed through the machine.

One end of shaft 21 is journaled in the sleeve 28, which sleeve is adapted to slide on the rod 29. A spring 30 on said rod 29 forces said sleeve 28 up against the adjustable stop-sleeve 31, the opposite end of said spring bearing against the nut 32, which is screwed on the rod 29. A twin sleeve 33 is arranged 10 to slide on the shaft 34 and the rod 35, both shaft and rod being supported at one end in bracket 36, and at the opposite ends they are supported by the bearing 37 and bracket 38, respectively. The bevel-gear 27 is secured 15 to the shaft 34. An adjustable stop-sleeve 39 is secured to said shaft adjacent to said sleeve 33. An arm 40 projects at right angles from sleeve 33, in the end of which is provided the bearing for the end of the shaft 21, adjacent 20 to the bevel-gear 26. The rod 35 carries a spring 41, which presses sleeve 33 up against the adjustable stop 42 on shaft 34. A nut 43 is screwed on rod 35, so that the tension of the spring 41 may be suitably adjusted. The 25 normal relative position of wheel 20 with respect to wheel 23 is adjusted by means of the stops 31 and 42, the sleeves 28 and 33, respectively, being forced up against them by means of the springs 30 and 41. A gear 44 is 30 secured at the rear end of shaft 34 and is driven by a gear 45, which is of somewhat greater width than gear 44. These gears are driven at such a rate that the surface speed of the opening-wheel 20 at its corrugated or 35 burred portion is the same as that of the fluted portion of the rolls 1.

The operation of the above-described machine is as follows: The piece of leather to be split is placed between the rolls with one edge 40 against the guide 9. The leather will be carried down between the rolls, the edge adjacent to guide 9 being straightened by knife 4 and then forced upon the splitting-knife 3, the end of which is set at a sufficient distance 45 from the straightening-knife 4 so that a small section will be left unsplit, and thus the divided sections will not be completely severed. The strip which is removed by the knife 4 is discharged into the spout 8. As the piece of leather passes between the rolls the latter will be forced apart a distance according to the thickness of the leather, the bearings 2 sliding in the slots in the frame, forcing out the upper ends of the levers 10 and causing the slides 12 to be forced upwardly through the medium of the links 14, drawing up the rods 15 and compressing the springs 17. As

the length of the levers 10 and their connecting-links 14 are respectively the same, the extent of the separation of the rolls from the splitting-knife will also be the same, so that if the knife is centrally adjusted the leather will always be split through the middle. Owing to the arrangement above described the amount of friction between the movable 75 journaled boxes and the frame is reduced to a minimum and there is no danger of any lost motion between the toggle-levers, through which the springs 17 act to force the rolls together, as each part of the toggle is pivoted to the other without any sliding joints, and the springs always draw the parts of the toggle in the same direction, so that there will be no chance for lost motion, even if the joints become badly worn from use. The 80 force which acts on the journaled boxes to press them toward each other acts substantially in line with the line of motion of said boxes, so that even if the boxes fit rather loosely in their slots there is no tendency for 85 them to be moved laterally or to bind in the slots, as in other devices of this class. With my arrangement of equalizing-levers and the consequent freedom from binding and friction the tension of the springs 17 need only 90 be enough to overcome the tension of spring 18 and cause the rolls to grip the leather with a pressure sufficient to force the leather onto the splitting-knife. As springs 17 and 18 are 95 in equilibrium, as before stated, it follows 100 that it takes only a comparatively light pressure to force the rolls apart, and as the outward movement of the rolls is slight under most conditions but little of the expanding force of the springs 18 will be lost when the 105 rolls are in their outermost position. This is important, for if a considerable force is necessary to spread the rolls apart the leather will not be split through the middle, owing to the fact that the flesh side of the leather will 110 yield more readily to the pressure of the rolls than the grained side. My device has been found to split the leather with such accuracy that a comparatively thin piece of leather 115 after having been split once may be passed through the machine a second time and split again, thus nearly quadrupling the original surface. Many small pieces of leather which are too small for use, even after having been once split, will thus be rendered useful, and 120 a piece which when split once would have made only part of a lift of a heel when split a second time will make a whole lift. As solid heels—that is, heels made of whole lifts—are more valuable than pieced heels, it is obvious 125 that the value of small pieces may be materially increased by being split twice. After the leather piece is split to the hinge at one edge it will first be partially opened by the thickened back of the splitting-knife, and as 130 it descends the lower edge thereof, if it happens to be horizontal or nearly so, will first strike on the inclined portions 20" 20" of wheel 20 and will be opened somewhat more

and prevented from striking or catching on the shaft. It then passes between the wheels 20 and 23, the burred portions 22 of wheel 20 engaging the split side on opposite sides of the connecting-hinge, the groove therein coming opposite the hinge, so that there is no danger of its being broken. The cylindrical portion 23 of wheel 20 engages the leather directly opposite the burred portions 22 of wheel 20, spreading out the piece flat ready for use. As the piece is opened the square edges on the leather, which come together when the leather is spread out, are turned toward each other in the groove 25 of wheel 23, so that the opening operation is more easily and perfectly accomplished and the edges of the leather are not blunted. As the surface speed of the burred portions 22 is the same as that of the fluted portions of the rolls 1, 20 the leather pieces will be spread as fast as they are forced onto the splitting-knife, and as the latter is set slightly below the plane of the axes of the rolls the burred wheel will draw the leather piece down after it has left the rolls, and thus materially assist in the splitting operation.

The stops 31 and 42 are adjusted so that wheels 20 and 23 are just out of contact. When the leather passes between these 30 wheels, the sleeve 28 will slide on rod 29, compressing spring 30, and sleeve 33 will slide on rod 35, compressing spring 41, and at the same time said sleeve 33 will come into engagement with collar 39, causing shaft 34 to slide in bearings 36 and 37. The bevel-gears 26 27 must obviously remain in engagement and the gears 44 and 45 will remain in engagement, owing to the additional width of the latter. The wheels 20 and 23 will thus be separated according to the thickness of the leather.

In order that the splitting-knife 3 may be properly adjusted, it must be capable of three adjustments. The support for this knife is shown in detail in Figs. 7, 8, and 9. A main brace 47 is secured at its ends to the two end frames *a* and *b*. Said brace is provided with a dovetail groove, in which the support 48 may be vertically adjusted by means of the screws 52 and 53, which bear on opposite sides 45 of the projection 49 of support 48 and which are screwed into the projections 50 and 51 of brace 47. The upper end of support 48 is provided with a dovetail groove in which the knife-support 54 may be horizontally adjusted. This support 54 is provided with a lug 55, which is notched at 58 to receive a screw 56. This screw 56 is threaded into support 48 and is provided with flanges 57 57, which engage the opposite sides of lug 55, so that 50 when screw 56 is turned in either direction the knife-support will be horizontally adjusted. The knife is secured to the vertical face 59 of support 54 by means of screws 56, which pass through slots 60 in the knife. A 55 screw 61, provided with an eccentric projection 62, engages an aperture in the knife. The knife is adjusted longitudinally by loos-

ening screw 60 and turning the screw 61. If the splitting-knife is adjusted so that the forward end is in line with the straightening-knife 4, the two halves of the leather will be separated, as is obvious.

Although I have described my arrangement of toggle-levers for equalizing the separation of the rolls in connection with a scrap-leather-splitting machine, it is obvious that this arrangement may be advantageously used in connection with any splitting-machine in which it is desired to have the rolls separate automatically and uniformly.

Having described my invention, what I claim as new, and desire to secure by Letters Patent, is as follows:

1. The combination in a leather-splitting machine, of a pair of feed-rolls journaled at each end in movable bearings, guideways between which said bearings slide, a pair of levers pivoted at each end of the frame, arranged to engage the outer sides of said bearings, a single spring for each pair of levers, connections between said springs and levers whereby said levers will force said rolls toward each other, substantially as described.

2. The combination in a leather-splitting machine of a pair of feed-rolls, journaled at each end in movable bearings, guideways between which said bearings slide, a pair of levers pivoted at each end of said frame, one end of each lever being arranged to engage the outer side of each bearing, a central block arranged to move at right angles to the line of motion of said bearings, links connecting the opposite ends of said levers with said blocks, springs arranged to draw each block downward, whereby said levers will force said rolls toward each other, substantially as described.

3. The combination in a leather-splitting machine, of a pair of feed-rolls, movable bearings in which said rolls are journaled, guideways on which said bearings slide, a pair of levers pivoted adjacent to said guideways on a fixed part of the machine and arranged to engage said bearings and force them together, said levers acting on said bearings substantially in line with the line of motion of said bearings, a pivotal connection between said levers and a spring acting on said levers to force said rolls toward each other.

4. In a leather-splitting machine of the class described, an opening or spreading device consisting of a burred wheel carried by a shaft, suitable connections for causing said wheel to rotate at the same surface speed as that of the main feed-rolls, a cylindrical wheel journaled to rotate freely directly opposite said burred wheel, each of said wheels having a central annular groove, said grooves being located in the central plane of the splitting-knife.

5. In a leather-splitting machine of the class described, an opening or spreading device, consisting of a burred wheel carried by a shaft, and having a central annular groove,

5 suitable connections for causing said wheel to rotate at the same surface speed as that of the main feed-rolls, a cylindrical wheel journaled to rotate freely directly opposite said burred wheel, said wheels being located directly below the splitting-knife.

6. In a leather-splitting machine of the class described, an opening or spreading device consisting of a wheel carried by a shaft, said 10 wheel having a burred portion located beneath the back of the splitting-knife and a tapered portion extending from each side of said burred portion to the shaft, a cylindrical idle-wheel located opposite said burred wheel, 15 and means for causing said burred wheel to rotate at the same surface speed as that of the feed-rolls.

7. In a leather-splitting machine of the class described, an opening or spreading device 20 consisting of a shaft having an enlarged portion located beneath the back of the splitting-knife, a tapered portion extending from each side of said enlarged portion to the shaft and a roll journaled in front of said enlarged portion, 25 said parts being arranged so that the unsevered portion will pass between said enlarged portion and said roll.

8. In a leather-splitting machine of the class described a pair of feed-rolls, a splitting-30 knife arranged therebetween, a bracket having a flat vertical face on the rear side thereof arranged at right angles to said splitting-knife and a short distance in front of said knife, a straightening-knife having a flat 35 shank which is secured to said face, the cutting edge thereof being above the upper end of said face, a spout extending downwardly on the front side of said bracket from the upper end of said face, said spout being adapted 40 to receive the chips from the straightening-knife and conduct them free of the machine, substantially as described.

9. In a leather-splitting machine having 45 two end frames, a splitting-knife, an adjustable support therefor consisting of a bracket connecting said end frames, having a vertical groove therein, a support adapted to be adjustably secured in said groove, a horizontal groove in the top of said support, a knife-50 holding support adapted to be adjustably secured in said horizontal groove and having a vertical face at one end thereof extending at right angles to said horizontal groove, means for adjustably securing said knife to said vertical face so that it may be moved horizontally, whereby said splitting-knife is provided with three adjustments.

10. In a leather-splitting machine of the class described, the combination of the main 60 feed-rolls, the splitting-knife therebetween, an angular guide adjustably mounted in front of said knife and having a grooved, vertical face, the center of said groove being in the central plane of said knife.

65 11. In a leather-splitting machine of the class described the combination of the main feed-rolls, the splitting-knife therebetween,

an angular guide mounted in front of said knife having a vertical face, said face being in the central vertical plane of said knife and 70 means for adjusting said guide horizontally with respect to said knife.

12. In a leather-splitting machine of the class described, a spreading or opening device consisting of a burred wheel carried by 75 a shaft, bearings for supporting said shaft, sleeves carrying said bearings, rods arranged at right angles to said shaft on which said sleeves slide, stops at one side of said sleeves, springs for pressing said sleeves against said 80 stops, means for rotating said shaft, and an idle-wheel mounted directly in front of said burred wheel, substantially as described.

13. In a leather-splitting machine of the class described, a spreading or opening de- 85 vice consisting of a burred wheel carried by a shaft, bearings for supporting said shaft at each end, sleeves carrying said bearings, rods arranged at right angles to said shaft on which said sleeves slide, stops at one side of said 90 sleeves, springs for pressing said sleeves against said stops, means for rotating said shaft, consisting of a bevel-gear carried at one end thereof, a shaft at right angles to the wheel-shaft carrying an intermeshing bevel- 95 gear and journaled in one of said sleeves, means for preventing said latter shaft from sliding therein, means for driving said shaft, and a second wheel journaled in front of said burred wheel, substantially as and for the 100 purpose set forth.

14. The combination in a leather-splitting machine of a pair of feed-rolls, sliding bearing-boxes in which said rolls are journaled, a slot in which said boxes slide, a pair of levers pivoted adjacent thereto, each lever being arranged to engage its bearing-box at the outer side thereof, links connecting said levers, and a spring acting on said levers to press said bearing-boxes toward each other. 110

15. The combination in a leather-splitting machine of a pair of feed-rolls, sliding bearing-boxes in which said rolls are journaled, a slot in which said boxes slide, a pair of levers pivoted adjacent thereto, each lever being arranged to engage its bearing-box at the outer side thereof, links connecting said levers, a spring acting on said levers to press said bearing-boxes against each other, and a spring interposed between said bearing-boxes 115 and acting in opposition to said first-named spring, the tension of said springs being adjusted so that the parts are in equilibrium when the rolls are slightly separated.

16. The combination in a leather-splitting 125 machine of a pair of feed-rolls, sliding bearing-boxes in which said rolls are journaled, a slot in which said boxes slide, a pair of levers pivoted adjacent thereto and adapted to move said rolls toward each other, a spring acting 130 on said levers to force said rolls together, and a spring interposed between said bearing-boxes and acting in opposition to said first-named spring, the tension of said springs

being adjusted so that the parts are in equilibrium when the rolls are slightly separated.

17. The combination in a leather-splitting machine of a pair of feed-rolls, sliding bearings in which said rolls are journaled, means for forcing said rolls together consisting of a single spring and suitable connections between said spring and said rolls, and a spring interposed between said bearing-boxes acting in opposition to said first-named spring, the tension of said springs being adjusted so that the parts will be in equilibrium when the rolls are slightly separated.

18. The combination in a leather-splitting machine of a pair of feed-rolls, sliding bearing-boxes in which said rolls are journaled, a pair of levers pivoted adjacent thereto, each lever being arranged to engage its bearing-box at the outer side thereof, the portion of said levers which engages said boxes having a curved face, a pivotal connection between said levers and a spring acting on said levers to press said boxes toward each other.

19. The combination in a leather-splitting machine of a pair of feed-rolls, sliding bearing-boxes in which said rolls are journaled, a slot in which said boxes slide, a pair of levers pivoted adjacent thereto, each lever being arranged to engage its bearing-box at the outer side thereof, the portion of said levers

which engages said boxes having a curved face, links connecting said levers, and a spring acting on said levers to press said bearing-boxes toward each other.

20. The combination in a leather-splitting machine of a pair of feed-rolls, a pair of sliding bearings in which said rolls are journaled, a slot in which said bearings slide, a pair of levers pivoted adjacent to said bearings and adapted to move the same toward each other, links connecting said levers, a spring acting on said levers to force said rolls together, said levers being arranged so that the force with which they act on said rolls is exerted in approximately the same line as the line of motion of the latter.

21. The combination in a leather-splitting machine of a pair of feed-rolls, a slot in which said rolls are adapted to slide, a pair of levers pivoted adjacent thereto and adapted to move said rolls toward each other, links connecting said levers, and a spring acting on said levers to force said rolls together.

In testimony whereof I have affixed my signature in presence of two witnesses.

JAMES BUSFIELD.
